The ornamental design for a mobile phone, as shown and described.

DESCRIPTION

FIG. 1 is a front perspective view of a mobile phone showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion shown in FIG. 1; and,

FIG. 9 is an enlarged view of the encircled portion shown in FIG. 4.

The contours of the claimed right side portion shown in FIGS. 3 and 5 are a mirror image of the contours of the claimed left side portion shown in FIGS. 1, 3, 4, 8, and 9.

The dash-dot broken lines depict unclaimed portions of the mobile phone only and form no part of the claimed design.

The dot-dash broken lines in FIGS. 1, 4, 8, and 9 indicate portions of the claimed design shown on an enlarged scale in FIGS. 8 and 9.
